(57) **CLAIM**

The ornamental design for a table, as shown and described.

DESCRIPTION

FIG. 1 is a perspective view of the table;
FIG. 2 is top view of the table;

FIG. 3 is a bottom view of the table;

FIG. 4 is a side view of the table;

FIG. 5 is an opposite side view of the table;

FIG. 6 is a perspective view of the table in an alternative
configuration; and,

FIG. 7 is a perspective view of one of the components of the
table isolated for clarity of illustration.

The even-spaced broken line portions of the figures are
included to show portions of the article that form no part of
the claimed design.

1 Claim, 7 Drawing Sheets
